H. T. WINSTON,
DIRECTION SIGNAL,
APPLICATION FILED MAY 15, 1916.

1,240,639.

Patented Sept. 18, 1917.

UNITED STATES PATENT OFFICE.

HOLLIS T. WINSTON, OF WASHINGTON, DISTRICT OF COLUMBIA.

DIRECTION-SIGNAL.

1,240,639.

Specification of Letters Patent. Patented Sept. 18, 1917.

Application filed May 15, 1916. Serial No. 97,548.

To all whom it may concern:

Be it known that I, HOLLIS T. WINSTON, a citizen of the United States, residing at Washington, in the District of Columbia, 5 have invented new and useful Improvements in Direction-Signals, of which the following is a specification.

My invention relates to improvements in signals and more especially to devices for 10 signaling to or from moving vehicles. It is more especially intended for use with automobiles, but it may also be used for traffic or like signals.

My invention will be understood by reference to the accompanying drawings in which similar parts are indicated by corresponding reference symbols throughout the several views.

Figure 1 is a view in front elevation of 20 this improved signal in the extended or indicating position.

Fig. 2 is a view in side elevation with the signal in retracted position.

Fig. 3 is a view in section taken on the 25 line 3—3 on Fig. 2 looking in the direction of the arrow.

Fig. 4 is a view in section taken on the line 4—4 on Fig. 3 looking in the direction of the arrow.

Fig. 5 is a fragmentary view similar to 30 Fig. 3, of a modified form.

Fig. 6 is a fragmentary view in side elevation of Fig. 5.

Referring first to Figs. 1, 2, and 3, the 35 signal is intended to simulate the human hand, and in order to stow same in as small a casing as practicable this hand is preferably made of a plurality of members mounted on a common pivot.

In the hand shown the member 1 shows 40 the index finger of the hand and 2 shows the other three fingers of the hand, said fingers being represented in the closed position. These two members 1 and 2 are mounted on a pivot pin 3. These two members, when 45 in the retracted position, are inclosed in a flat rectangular box B, having the top, bottom and three sides closed, the fourth side being closed by the flange plate 5 and the bead 6, which project from the member 1 and form a cover for the open side of the box. This side of the box is provided with a shoulder 4 to serve as a stop for the member 1 when the signal is thrown to the horizontal position, as indicated in Fig. 1.

In order that the parts composing the hand may be stowed in a small space, the

member 2 is free to swing through a limited angle about the pivot 3 independently of the member 1, this swinging movement of 60 the member 2 being limited by any suitable stop whereby one of the members is caused to engage the other at a predetermined movement of the travel of the two. This may be accomplished in a variety of ways, 65 for instance having the pin 7 project from the member 2 and engaging in a slot 8 in the member 1.

10 represents a wire or cord connected to the heel of the member 1 in rear of the 70 pivot pin 3, as shown, which cord or wire may be connected to any suitable operating device, as the ring 11. An antifriction roller 12 may be provided for this wire or cord 10, 75 and any suitable shock absorber may be provided, such as the coil spring 13 mounted in a loop of the cord or wire, which coil spring will tend to prevent excessive strain on the members of the signal when the cord or wire is sharply pulled, thus rendering 80 it practicable to use light sheet metal in their construction.

It will be obvious that the signal may be moved to the horizontal position, as shown in Fig. 1, by a pull on the cord or wire 10, 85 and may be allowed to swing to the closed position by gravity, or the closing movement may be effected by a direct push on the wire 10; but automatic means may be used for bringing the signal to the retracted 90 position, such as the spring 9, which is wrapped about the pivot 3 and engages the interior of the casing and also engages the flange 5, as shown in Fig. 1.

So as to prevent rattling, I provide a 95 spring 15 adapted to engage the point of the member 1 when the latter is in the retracted position shown in Fig. 3. In order to further prevent rattling, a lining 14 of felt or other soft material may be applied 100 to the inner rear face of the casing, and the flange 16 may be provided on the member 2 to engage said lining and to prevent the same from being cut by the rear face of the member 2. This casing may be attached to 105 the vehicle, the post, or other support in any convenient way, as by the metal strips 30 and 31.

It will be seen that the flange 5 and rib 6 serve as a cover for the open side of the 110 casing when the signal is in the retracted position, and this casing will keep out dust, snow, sleet, or other foreign matter.

When a straight edge casing is used, it

will be necessary to cut away a small portion of the edge of the flange and of the bead, as shown in Fig. 2, so that the inner end of the signal members may be free to swing in and out of the casing, thus leaving small cracks between the hinged cover and the body of the casing.

These cracks need not be a serious objection; but if desired they may be dispensed with entirely by the construction shown in Figs. 5 and 6, in which is illustrated a modified form of mounting the flange section 1 of the hand so that it will form a complete cover for the open side of the casing at all times. In this form the front and rear of the casing at the top are struck out or increased in depth on both faces to receive the full width of the flange and bead between them. The rear portion of the flange section 20 is formed upon the arc of a circle having its center at the pivoted point and the bead and flange carried thereabout. The top of the casing side 4^a is curved correspondingly to allow the curved portion of the hand to rotate thereunder and to act as a stop when the flange section is in the horizontal position. The front and rear walls of the casing are curved upon a concentric arc from the termination of the curved side 4^a to the edges of the open sides therebelow but upon a lesser radius, so that the bead on one side and the flange on the other side will travel thereover and in the retracted position of the hand the flange and bead will form a complete closure from the termination of the top side 4^a to the bottom of the casing.

It will be obvious that various modifications might be made in the herein described apparatus and in the construction, combination and arrangement of parts which could be used without departing from the spirit of my invention.

Having thus described my invention, what I claim and desire to secure by Letters Patent of the United States is:

1. A signaling device of the character described comprising a casing closed on all sides but one, a pivot pin passing through said casing parallel to the open side thereof, a plurality of signaling members pivoted on said pin and having a limited angular movement relative to each other about said pivot pin, said members over-lapping each other when in the retracted position, and one of said members being provided with laterally projecting flanges adapted to close the open side of said casing when the signaling members are in the retracted position, with means for swinging said members about said pivot pin into and out of said casing.

2. A signaling device of the character described comprising a casing closed on all sides but one, a pivot pin passing through said casing, parallel to the open side thereof, a pair of signaling members pivoted on said pin, comprising an inner and an outer member, the outer member being longer than the inner and being provided with laterally projecting flanges adapted to form a cover for the open side of said casing when the two members are in the retracted position, the two members having a limited angular movement relative to each other about said pivot pin, said members over-lapping each other when in the retracted position, with means for swinging said members about said pivot pin into and out of said casing.

3. A signaling device of the character described comprising a casing closed on all sides but one, a pivot pin passing through said casing, parallel to the open side thereof, a pair of signaling members pivoted on said pin, comprising an inner and an outer member, the outer member being longer than the inner and being provided with laterally projecting flanges adapted to form a cover for the open side of said casing when the two members are in the retracted position, the two members having a limited angular movement relative to each other about said pivot pin, said members over-lapping each other when in the retracted position, a spring catch secured in said casing and adapted to engage the fore end of said outer member, and means for swinging said members about said pivot pin into and out of said casing.

4. A signaling device of the character described comprising a casing closed on all sides but one, a pivot pin passing through said casing, parallel to the open side thereof, a pair of signaling members pivoted on said pin, comprising an inner and an outer member, the outer member being longer than the inner and being provided with a laterally projecting flange adapted to form a cover for the open side of said casing when the two members are in the retracted position, and also to engage the outer edge of said inner member to swing it back into place in said casing, the two members having a limited angular movement relative to each other about said pivot pin, said members over-lapping each other when in the retracted position, and a wire or cord secured to the heel of said outer member for swinging both of said members about said pivot pin.

HOLLIS T. WINSTON.
